1

Relatively long tube coils, preferably of small internal diameter, are being increasingly employed as steam generating tubes in modern steam generators. Their principal advantages are that they take up considerably less space, provide a highly effective heating surface, and finally—particularly at high steam pressures—save a great deal of weight owing to the small tube wall thickness required. Whether the circulation in the coils is forced or natural, the water will not flow steadily through them, but will pulsate, causing strong forward flow impulses to alternate with insignificant rates of flow or even retrogression.

These pulsations may in certain circumstances cause circulation troubles and occasionally endanger the safe working of the plant. If, as is usually the case, a large number of tube coils are connected to a common inlet header receiving the circulating water from a steam separator common to several inlet headers, the pulsations may cause steam to enter the inlet headers periodically or accidentally. Although the forward flow impulses will eventually force that steam back into the steam generating tubes, its movements may in the meantime have affected the circulation process unfavourably.

Should, for instance, steam bubbles enter not only the inlet header but also the tubes supplying circulating water to that header, any steam bubbles which for some reason, in spite of the forward flow, remain in the descent tubes may to a greater or less extent hinder the circulating water's entering the inlet header, and consequently also the tube coils. Particularly if the descent tubes carry the water to the inlet header by gravity, thus creating a natural circulation in the tube coils, steam entering such descent tubes may endanger the whole circulation, for a natural circulation is produced and maintained by the difference in specific gravity of the column of water in the descent tubes and that of the column of steam emulsion in the steam generating tubes and the ascent tubes. If enough steam should enter the descent tubes, this difference in weight might diminish to insignificance, which would naturally have an adverse effect on the circulation. The result may be that too little water will reach the tube coils for the plant to be worked safely.

In the event of the tube coils being attached to the inlet header at different levels, any steam forced into them by the pulsations may also substantially alter the distribution of the circulating water to the different tube coils. The steam will

2

rise to the top of the header and may even have time to collect there in sufficient quantity to displace part of the water before being again forced into the coils. In any case the steam will be concentrated to the upper part of the inlet header and the topmost coils will accordingly be fed not with water alone but with a mixture of water and steam which may contain so little water that this would all boil away before reaching the other ends of the coils where the gradually increasing salt deposits might quickly result in tube breaks.

The problem of preventing these detrimental effects of the pulsating flow in the steam generating tubes may be solved in two fundamentally different ways. As the trouble is actually due to steam entering the header serving to distribute the water to the tube coils, the steam can either be prevented from reaching as far as that header or allowed to enter the header to be removed from there as quickly as possible and in such a way that it will cause no trouble of the kind described above.

Devices are known which will solve the trouble in the first of these ways. Such are for instance the choke nozzles fixed in the steam generating tube inlets of the "La Mont" forced circulation boilers. Although satisfactory reliability in working has gradually been achieved by this means, it has several attendant drawbacks. For an effective stabilization of the forward flow in the steam generating tubes, the pressure reduction in these choke nozzles must be of the same order of magnitude as the loss of pressure in the tube coils in overcoming the resistance to the flow. The coils must therefore be made substantially shorter than if the available pressure could be used solely for overcoming the resistance. Further, there will be a relatively large risk of these rather small nozzles (down to 4 mm. in diameter) silting up. To eliminate that risk it has proved necessary to provide each nozzle with a kind of strainer with a large number of smaller holes than that of the nozzle. But even such strainer may silt up, and the descent tube to the inlet header has therefore also had to be provided with a large strainer which must be inspected occasionally and the silt cleaned out.

The present invention solves the above problem by the second of the methods mentioned above. Any steam entering the inlet header is removed by one or more special escape tubes and passes through them to some steam carrying part of the steam generator higher than the inlet header and behind the steam generating tubes in the

circulating system, e. g. to the outlet header collecting the steam from the steam generating tubes or to the ascent or collecting tubes leading the mixture of steam and water from that outlet header to the steam separator or—finally—directly to the steam separator.

The structural details and the manner in which this device functions are indicated in the attached drawings, Figs. 1-5.

Figs. 1a (vertical view) and 1b (horizontal section) represent a steam generator designed for natural circulation. The steam generating surface is heated by convection and consists of the tube coils 1 placed in a horizontal gas flue through which the hot gases pass in the direction of the arrows. The gases are here supposed to come from some suitable fireplace or furnace, in which latter case the steam generator would be a "flue-gas" boiler. From the steam separator 6 the water is taken through the descent tube 4 through a water seal to the lower end 5 of a vertically mounted inlet header 2. From this the water passes into tube coils 1 assembled in horizontal layers one above the other; each coil is made up of a number of straight tubes placed at right angles to the direction of the gas flow and connected to one another by sections of tubes bent to an angle of 180° to form continuous steam generating tube coils. The steam generated in these coils then goes to the outlet header 3 together with any circulating water that has not yet been vaporized. From the outlet header the mixture of steam and water passes through the ascent tube 12 to the steam separator 6 in which the water is separated from the steam. From the upper end 7 of the inlet header the previously mentioned escape tube 8 leads directly to the steam-containing part of the steam separator 6.

Helical or oblique guide vanes are fitted inside the descent tube 4 at the flange 5 which connects it from below to the inlet header to impart a rotatory movement to the circulating water before it enters the inlet header. These guide vanes 9 may for example be made as shown in Figs. 2a (vertical section) and 2b (horizontal view from above). The vanes are there made of thin, plain plates set at a certain angle—say 45°—and welded both to the inside of the pipe wall and to a separate small pipe 10 for the purpose of giving firmness to the whole guide vane structure. A similar device may if desired be placed inside the escape tube 8, close to its inlet opening, in order to stop the rotatory movement of the water when no longer required. A reduction of the flow resistance in the escape tube might thus be obtained.

Owing to the great horizontal lengths of heating surface of these tube coils, strong pulsations will be set up there, and the steam generated in them will not only flow forward, but will also periodically be flung back towards the inlet header 2. As any steam entering the vertical inlet header will successively rise towards its top, the upper part of the header will contain a greater proportion of steam than the lower with consequent great risk of too much steam and too little water entering the highest tube coils. Thanks to the escape tube 8, by which such steam as is not immediately drawn into the tube coils in passing through the header will successively escape, this risk is substantially reduced. By suitable dimensioning of the guide vanes according to Fig. 2 described above, a rotatory movement is imparted to the water in the inlet header

which has the effect of collecting practically all the steam that enters the header in its centre while flinging the water outwards to its periphery. The advantage of this is that all the tube coils, in which the pressure is lower than in the inlet header, will be filled only or mainly with water and their satisfactory cooling thus secured, irrespective of whether they are at a higher or lower level in the header. At the same time all the steam collected in the centre of the header will escape by the outlet pipe 8 to the steam separator 6.

In this way a double circulation system is set up with the descent tube 4 common to both. Part of the water flowing through the descent tube 4 will enter the tube coils, where a minor portion of it is converted into steam. The resultant mixture of water and steam flows into the outlet header 3 and from there by the ascent tube 12 to the steam separator 6 in which the steam is separated from the water. Another portion of the water from the descent tube 4 will in the inlet header be mixed with steam coming back into the header from the tube coils and will leave the header—still mixed with the steam—by the escape tube 8 to the steam separator 6. Experiments made have proved that it is easy to so dimension the tubes that even if the quantities of steam escaping through the escape tube are relatively small, the quantity of water carried with it may be many times larger than that which flows into the tube coils. This does not mean that the circulation through the escape tube will to any appreciable extent rob the circulation through the heating coils of its water, since the amount of water flowing through the descent tube 4 will also be several times larger than it would be if there were no escape tube 8. The greater the quantity of steam flowing back into the inlet header, the greater will also—up to a certain maximum which in practice need not be exceeded—the quantity of water circulating through the escape tube be.

This circumstance has two exceedingly favourable secondary effects over and above the solution of the problem which is the object of the present invention.

One is that the reaction on the flow of water in the descent tube of any pulsations in the individual steam generating tubes will be considerably reduced. More especially will a reversal of the direction of the flow in the descent tube be made more difficult, and any inflow of steam into its vertical portion is therefore prevented. This is directly connected with the manifold increase of the rate of flow of the water in the descent tube by the introduction of the escape tube. Substantially stronger back pressure impulses from the tube coils will therefore be required for a reversal of the direction of the flow in the descent tube than was the case before the escape tube was introduced. This provides the requisite safety margin to prevent any disturbances of the circulation of this kind. That safety margin may be said to consist in the aggregate kinetic energy of the water flowing through both the descent and escape tubes.

The other favourable secondary effect consists in a substantial increase in the ability of the generator to withstand, without failure, the stresses of sudden pressure reductions due to sudden increases in the quantity of steam taken out of it. This ability mainly depends on the rate of flow of the water in the descent tubes.

The risk of failure lies in that the water in the

feed pipes may begin to boil when the pressure suddenly drops, which might prevent the circulation. But if the pressure drop, which is initiated in the steam separator, is not too rapid, the descent tube will be fed continuously with water which owing to the pressure drop has given off steam in the steam separator and has accordingly assumed the lower temperature corresponding to the lower pressure. This water will flow towards parts where the pressure is higher and its vaporization will therefore cease. On account of the hydrostatic pressure difference, the water in the lower parts of the descent tubes is subjected to higher pressure than the water in the steam separator. The faster the downward flow of water in the descent tube, the quicker can the pressure in the steam separator be reduced without danger of vaporization in the descent tube. The limit is reached when the increase of pressure due to the greater depth of the water below its free surface in the steam generator balances the continuous reduction of the steam pressure in the steam separator.

As the backward flow of steam into the inlet header and escape tube will not substantially increase the flow of water in the descent tube, the present invention will automatically also increase the ability of the steam generator to withstand rapid reductions of the steam pressure. What has now been said applies to heavily loaded steam generators, for only when much heat is supplied to the tube coils will the pulsations in these be strong enough to force the steam back periodically to the inlet header. They will not be able to do so when the heat load is low, and there will consequently be no flow of water through the escape tube. A rapid lowering of the pressure will then cause the water to boil sooner in the escape tube than in the descent tube, which is of course flowing downwards, i. e. towards levels of higher pressure. This will produce a previously non-existing difference of weight between the water column in the descent tube and that in the escape tube, causing the steam emulsion in the escape tube to begin to flow rapidly upwards, increasing the rate of flow of the water in the descent tube proportionately. This provides increased security against boiling in the descent tube, and accordingly also against disturbances of the circulation. Vaporization in the escape tube will increase with falling steam pressure, which accordingly also applies to the rate of flow in the descent tube. The margin of safety as regards disturbances of the circulation will thus increase with the risk of such disturbances, i. e. with the rate at which the pressure drops. The escape tube thus provides increased security against disturbances of circulation connected with any sudden reduction of pressure in the steam generator, whether the pressure in the generator is high or low.

Fig. 3 shows, inside the dot-and-dash line, how the tube coils are arranged on the wall of a steam boiler furnace to form what is called a "cooling wall," also serving to cool the brick-work and protect this from the intense heat radiated by the furnace flames. The same figures are used as in Fig. 1, and tube coils, descent tube, inlet header, outlet header, ascent tube, and escape tube may be easily recognized there. The essential difference is that the inlet header 2 is here horizontal. It might then be asked how it is that the periodical return flow of steam into the inlet header in this case will really

pass out by the escape tube 8 and not by the descent tube 4, seeing that both these tubes are connected to the inlet header at exactly the same level and that the steam ought therefore to flow into the one tube as easily as into the other. To make perfectly certain of the tubes' functioning in the desired manner, it is accordingly necessary to obstruct the entry of steam into the descent tube and to make it definitely more easy for the steam to enter the escape tube than the descent tube. This obstructive effect is achieved by the arrangement shown in Fig. 3 where the pipe is carried horizontally a not too short distance reckoned from the inlet header before it is bent upward, while the escape tube turns vertically upwards immediately on leaving the inlet header. This difference in the arrangement of the tubes, although not making the actual entry of the steam into tube 4 more difficult than into tube 8, will certainly prevent the steam reaching the vertical portion of the descent tube before sufficient steam has reached the vertical portion of the escape tube to make the difference in the specific gravities of the water column in the vertical portion of the descent tube on the one hand and the column of steam emulsion in the escape tube on the other large enough to set up a strong circulation which will compel the water to flow down the descent tube into the inlet header, and from this to the escape tube. The steam is thus prevented by the flow of the water in the opposite direction from passing through the descent tube instead of through the escape tube. The escape tube is not here connected directly to the steam separator, but to the outlet header, which with correctly dimensioned pipes is also possible.

Fig. 4a is a section of a vertical flue, in which the hot gases from some kind of furnace rise from below upwards, giving off their heat to a number of steam-generating tube coils. These coils are connected to a horizontal inlet header visible in section on the right of the drawing. The coils are taken direct to the steam separator 6. Fig. 4b shows the steam generator seen in Fig. 4a from the left, and in particular permits a study of the arrangement of the tubes at the inlet header. The water reaches the inlet header from the steam separator 6 through the descent tube 4 which—before entering the header 2—is bent to form a trap 13 to prevent any steam that might flow back to the inlet header finding its way through the vertical portion of the descent tube. The steam will therefore pass through the escape tube 8 direct to the steam separator 6. Here it is thus the trap 13 that obstructs any return flow of steam into the vertical portion of the descent tube, and so secures the functioning of the escape tube as an escape tube, and of the descent tube as a feed pipe, although they both connect the steam separator to the inlet header and are joined to the latter at the same level. As the tube coils 1 are connected to the lower side of the inlet header, any steam flowing back into this from the tube coils will, owing to its lower specific gravity, collect mainly at its top, and so be prevented from again entering the coils at the times when there is a forward flow into the openings to the tube coils. Water will thus always be supplied to the tube coils even though these may periodically discharge steam into the inlet header. An equal distribution of the circulating water to the several tube coils and accordingly also the satisfactory cooling of the coils while working are secured by this means.

The method mentioned above of attaching the tube coils to the lower part of a horizontal inlet header is intended to be used also in the arrangement according to Fig. 3, although this is not clearly marked in the drawing.

Fig. 5a shows a longitudinal section of the heating surface in a horizontal flue, consisting of pendant tube coils 1 made up exclusively of vertical tube portions connected by sections bent to an angle of 180°. Fig. 5b is a cross section of the same flue. The bottom tube coil is met by gas screens 14, between which the ashes fall down and can be raked out through the hand holes 17. These screens prevent the hot gases passing by the pendant convection surfaces. The ends of the coils are connected to two horizontal headers, the inlet header 2 and the outlet header 3. The inlet header is connected to the water-filled part of the steam separator 6. The other end of the inlet header is connected to the steam-filled part of the steam separator 6 by the escape tube 8, which has exactly the same function here as in previously described arrangements, i. e. to return any steam flowing back into the inlet header from the tube coils. The outlet header 3 is connected to the steam-filled part of the steam separator 6. In order to compel the descent tube to function as a feed pipe and the escape tube as an escape tube, the former is provided with a trap 13 immediately before entering the inlet header, thus preventing the back flow of steam from entering the vertical portion of the descent tube.

The water will circulate from the inlet header to the outlet header if only the steam separator 6 is placed at a sufficient height above the heating surface. The force producing this circulation is the difference in specific gravity of the column of water in the descent tube and the column of steam emulsion in the ascent tube 12 from the outlet header to the steam-filled part of the steam separator 6. A sine qua non of that circulation is thus that there must be only water in the descent tube 4 and a mixture of steam and water, rich in steam, in the ascent tube 12. That condition is continuously maintained by the arrangement described, for the descent tube 4 is the only one of the three tubes 4, 8, and 12 which leaves the steam separator at a point below its free water surface and is therefore capable of conveying water to the steam-generating surface in the flue, and at the same time the only one of the said three pipes in which steam from the steam-generating surface cannot enter as long as the escape tube 8 provides a free passage for any steam that may flow back into the inlet header. Incidentally, the return flow of steam can be substantially reduced by letting the water enter the tube coils at the ends situated where the flue gases, after having been cooled by the heating surface, pass beyond this. Less steam will therefore be generated there than at the other end of the heating surface, where the tube coils are connected to the outlet header where they encounter the hot flue gases before these are cooled. It is obviously not essential for the obstacle preventing the return flow of steam from entering the escape tube and not the descent tube to be a water trap as figured in Fig. 5b. The main thing is that the obstacle employed is sufficient to make descent tube and escape tube function as desired.

The said obstacle may for example be a choke nozzle which will coke off the pressure in the descent tube to a certain extent whenever the

water flows towards the inlet header. In order to enter the descent tube the steam must accordingly overcome that pressure, which it can never do in the inlet header provided the escape tube is sufficiently wide in diameter to allow the back-flow of steam to escape to the steam separator without increasing the pressure too much. The effect of such a choke nozzle will obviously be greater if it is made as shown in Figs. 6a and 6b. The opening 16 in the nozzle plate 15 is here located in its lowermost part, and sufficient steam must therefore accumulate in the inlet header 2 to depress the water to the top of the opening 16 before steam can force its way into the descent tube 4. If the escape tube 8 is sufficiently large this will be impossible, and an obstacle of this simple nature may therefore be quite sufficient to achieve the desired effect. The nozzle design may of course be used not only in the arrangement shown in Figs. 5a and 5b but also in all cases in which the tube coils come from horizontal inlet headers, thus also in the arrangements shown in Figs. 3 and 4.

When the steam generating tubes carry high heat loads the pulsations become very brisk and powerful, and large masses of steam will then periodically flow backwards towards the inlet header and the escape tube. The internal diameters of these must therefore be fairly large so as to give sufficient room for these quantities of steam. With a view to keeping down the dimensions of the inlet header and the escape tube, however, an effort to reduce the amount of back-flowing steam may be made. The previously mentioned, well-known method of placing choke nozzles in the openings of the steam generating tubes, which is employed in for example the "La Mont" boiler, may be used for that purpose. The drawbacks of this—the risk of the nozzles silting up and of a large portion of the available pressure being consumed in the choking process—may be avoided by making the nozzles large enough to avoid any risk of their silting up. At that size—e. g. when the nozzle orifice is not less than 12 to 15 mm. in diameter—only an insignificant portion of the available pressure will be lost, and at least 90% of it may as a rule be used for overcoming the flow resistance in the coils, and so make the employment of long coils practicable. Although it is of course impossible entirely to prevent a back-flow of steam into the inlet header by this means, the amount of such back-flow will be reduced to a fraction of the value it would otherwise attain, and the dimensions of inlet header and escape tube may therefore be substantially reduced without any risks of the circulation being disturbed.

The choke nozzles may for instance be constructed as shown in Fig. 7, where 3 is the inlet opening of the tube coil, which is attached to the wall of the inlet header 2. The choke nozzle 1 consists of an exteriorly slightly conical plug driven into the inlet opening of the tube coil which has previously been reamed to the same angle as the choke nozzle. Centrally in this cone is drilled a cylindrical hole of suitable diameter.

The devices now described, and the invention as a whole, are naturally not limited to the arrangements of the tubes shown in Figs. 1-6, but is equally applicable to all steam generators characterized by a number of parallel-coupled tube coils for steam generation of any form or shape, or to steam generating tubes of other designs connected to an arbitrarily situated inlet header.

75 What I claim is:

1. A steam generator for natural circulation comprising a plurality of parallel coupled steam generating tubes formed by tube coils of small internal diameter and great length; an elongated inlet header common to the inlet ends of said steam generating tubes, a steam separator above said inlet header and tubes; connections between said steam separator and said inlet header and steam generating coils arranged to form a closed circuit for water and generated steam with defined direction of flow in the steam generating tubes directed from said inlet header to all of said tubes; the connections between said inlet header and said steam separator consisting of at least one descent tube arranged for an uninterrupted flow of the circulation water from the water space of the steam separator by gravity to one end of the inlet header, the lowest point of said descent tube being disposed at least as low as the lower part of the inlet header, and at least one steam escape tube connected to the inlet header at the opposite end thereof above the connection points of the steam generating tubes therewith and to the steam separator above the level of the water therein and further being so dimensioned and arranged that it is able quickly to lead off from the upper portion of the inlet header to the steam space of the steam separator the steam quantities which now and then on account of irregularities in the circulation enter the inlet header and thus prevent these steam quantities from disturbing the circulation process in the circuit as a whole.

2. A steam generator for natural circulation comprising a plurality of parallel-coupled steam generating tubes formed by tube coils of small internal diameter and great length; an elongated inlet header common to the inlet ends of said steam generating tubes; a steam separator above said inlet header and tubes; connections between said steam separator and said inlet header and steam generating coils arranged to form a closed circuit for water and generated steam with defined direction of flow in the steam generating tubes directed from said inlet header to all of said tubes, the inlet openings of the steam generating tubes being at least so great that at the temporary occurring tendency of the steam-water mixture to flow back to the inlet header, not only water but also a part of the generated steam is allowed to enter said inlet header; the connections between said inlet header and said steam space consisting of at least one descent tube arranged for an uninterrupted flow of the circulation water from the water space of the steam separator by gravity to one end of the inlet header, the lowest point of said descent tube being disposed at least as low as the lower part of the inlet header, and at least one steam escape tube connected to the inlet header at the opposite end thereof above the connection points of the steam generating tubes therewith and to the steam separator above the level of the water therein and further being so dimensioned and arranged that it is able quickly to lead off from the upper portion of the inlet header to the steam space of the steam separator the steam quantities which now and then on account of irregularities in the circulation enter the inlet header and thus prevent these steam quantities from disturbing the circulation process in the circuit as a whole.

3. A steam generator for natural circulation comprising a plurality of parallel-coupled steam

generating tubes formed by tube coils of small internal diameter and great length; an elongated inlet header common to the inlet ends of said steam generating tubes; a steam separator above said inlet header and tubes; connections between said steam separator and said inlet header and steam generating coils arranged to form a closed circuit for water and generated steam with defined direction of flow in the steam generating tubes directed from said inlet header to all of said tubes, the inlet openings of the steam generating tubes being at least so great that at the temporary occurring tendency of the steam-water mixture to flow back to the inlet header, not only water, but also a part of the generated steam is allowed to enter said inlet header; the connections between said inlet header and said steam space consisting of at least one descent tube arranged for an uninterrupted flow of the circulation water from the water space of the steam separator by gravity to one end of the inlet header, the lowest point of said descent tube being disposed at least as low as the lower part of the inlet header, and at least one steam escape tube connected to the inlet header at the opposite end thereof above the connection points of the steam generating tubes therewith and to the steam separator above the level of the water therein and further being so dimensioned and arranged that it is able quickly to lead off from the upper portion of the inlet header to the steam space of the steam separator the steam quantities which now and then on account of irregularities in the circulation enter the inlet header and thus prevent these steam quantities from disturbing the circulation process in the circuit as a whole, this function of the escape tube being supported by obstruction means to the back-flowing steam in the descent tube and always permitting the water from the water space of the steam separator to pass continually in the defined direction of circulation, said escape tube being free of obstruction, whereby the back-flowing steam is forced to enter the escape tube in preference to the descent tube in escaping from the inlet header to the steam separator.

4. A steam generator as set forth in claim 3 in which the obstruction to the backflow of steam in the descent tube consists of a water seal arrangement in which the water passing to the inlet header is forced to pass a lower level than the level of the lowermost of the inlet ends of the steam generating tubes.

5. A steam generator as set forth in claim 3 in which the obstruction to the backflow of steam in the descent tube consists of an elongated substantially horizontal section of said tube on a level not essentially higher than the lower part of the inlet header.

6. A steam generator as set forth in claim 3 in which the obstruction to the backflow of steam in the descent tube comprises choking means in the descent tube.

7. A steam generator for natural circulation comprising a plurality of parallel-coupled steam generating tubes formed by tube coils of small internal diameter and great length; a vertical inlet header common to the inlet ends of said steam generating tubes; a steam separator above said inlet header and tubes; connections between said steam separator and said inlet header and steam generating coils arranged to form a closed circuit for water and generated steam with defined direction of flow in the steam generating

tubes directed from said inlet header to all of said tubes, the inlet openings of the steam generating tubes being at least so great that at the temporary occurring tendency of the steam-water mixture to flow back to the inlet header, not only water, but also a part of the generated steam is allowed to enter said inlet header; the connections between said inlet header and said steam space consisting of at least one descent tube arranged for an uninterrupted flow of the circulation water from the water space of the steam separator by gravity to the inlet header, and connected to the lower end of the latter, and at least one steam escape tube connected to the inlet header at the upper end thereof above the connection points of the steam generating tubes therewith and to the steam separator above the level of the water therein and further being so dimensioned and arranged that it is able quickly to lead off from the upper portion of the inlet header to the steam space of the steam separator the steam quantities which now and then on account of irregularities in the circulation enter the inlet header and thus prevent these steam quantities from disturbing the circulation process in the circuit as a whole.

8. A steam generator as set forth in claim 7 including means for effecting a rotary movement of the water about the vertical axis of the inlet header, said means being situated at the lower end of the said header, in order to get the now and then back-flowing steam collected in the center of the header and prevent it from re-entering the inlet ends of the steam generating tubes, thus securing an equal distribution of water in the said tubes.

9. A steam generator, as set forth in claim 2, in which the inlet header extends horizontally, the inlet ends of the steam generating tubes being situated in the lower portion of the said header, so that the backflowing steam will be collected in the upper part of the inlet header and from there lead to the escape tube, without having a possibility of re-entering the steam generating tubes.

10. A steam generator for natural circulation comprising a plurality of parallel-coupled steam generating tubes formed by tube coils of small internal diameter and great length, each of them made of a straight tube, which is bent back in at least two points, so that said tube will contain several straight tube portions of different direction, at least two of them together with the tube bend between them being situated in a horizontal plane; an elongated inlet header common to the inlet ends of said steam generating tubes; a steam separator above said inlet header and tubes; connections between said steam separator and said inlet header and steam generating coils arranged to form a closed circuit for water and generated steam with defined direction of flow in the steam generating tubes directed from said inlet header to all of said tubes, the inlet openings of the steam generating tubes being at least so great that at the temporary occurring tendency of the steam-water mixture to flow back to the inlet header, not only water, but also a part of the generated steam is allowed to enter said inlet header; the connections between said inlet header and said steam space consisting of at least one descent tube arranged for an uninterrupted flow of the circulation water from the water space of the steam separator by gravity to one end of the inlet header, the lowest point of said descent tube be-

ing disposed at least as low as the lower part of the inlet header, and at least one steam escape tube connected to the inlet header at the opposite end thereof above the connection points of the steam generating tubes therewith and to the steam separator above the level of the water therein and further being so dimensioned and arranged that it is able quickly to lead off from the upper portion of the inlet header to the steam space of the steam separator the steam quantities which now and then on account of irregularities in the circulation enter the inlet header and thus prevent these steam quantities from disturbing the circulation process in the circuit as a whole.

11. A steam generator for natural circulation comprising a plurality of parallel-coupled steam generating tubes formed by tube coils of small internal diameter and great length, each of them made of a straight tube, which is bent back in at least two points, so that said tube will contain several straight tube portions of vertical direction; an elongated inlet header common to the inlet ends of said steam generating tubes; a steam separator above said inlet header and tubes; connections between said steam separator and said inlet header and steam generating coils arranged to form a closed circuit for water and generated steam with defined direction of flow in the steam generating tubes directed from said inlet header to all of said tubes, the inlet openings of the steam generating tubes being at least so great that at the temporary occurring tendency of the steam-water mixture to flow back to the inlet header, not only water but also a part of the generated steam is allowed to enter said inlet header; the connections between said inlet header and said steam space consisting of at least one descent tube arranged for an uninterrupted flow of the circulation water from the water space of the steam separator by gravity to one end of the inlet header, the lowest point of said descent tube being disposed at least as low as the lower part of the inlet header, and at least one steam escape tube connected to the inlet header at the opposite end thereof above the connection points of the steam generating tubes therewith and to the steam separator above the level of the water therein and further being so dimensioned and arranged that it is able quickly to lead off from the upper portion of the inlet header to the steam space of the steam separator the steam quantities which now and then on account of irregularities in the circulation enter the inlet header and thus prevent these steam quantities from disturbing the circulation process in the circuit as a whole.

KARL FOLKE NORDLUND.
